UNITED STATES PATENT OFFICE

JOHN COOK, OF SYRACUSE, NEW YORK, AND JOHN C. SPENCE AND RAYMOND A. COLE, OF WORCESTER, MASSACHUSETTS, ASSIGNEES TO NORTON COMPANY, OF WORCESTER, MASSACHUSETTS, A CORPORATION OF MASSACHUSETTS

GRINDING MACHINE

Application filed January 12, 1928. Serial No. 246,237.

This invention relates to grinding machines of the type shown in the patent to Norton No. 762,838 and more particularly to a mechanism for positioning and moving the grinding wheel.

In grinding cylindrical objects it is often desirable to move the grinding wheel laterally and to position it accurately in a second grinding position. For example, in grinding cylindrical objects having a plurality of diameters, where it was necessary to grind close to a shoulder, the operator has heretofore had to move the heavy work table to bring the shoulder of the work piece into correct position relative to the side face of the grinding wheel. This requires considerable attention and skill on the part of the operator to position the table accurately relative to the operative face of the grinding wheel and avoid injuring the work or the wheel. This wastes valuable time in carrying on duplicate grinding operations.

Also, certain types of grinding operations require reciprocating the grinding wheel axially through a short stroke. This is often necessary where the wheel is fed directly into the work and care must be taken to avoid leaving abrasive grain markings on the work. Such a mechanism is limited in its utility unless the stroke of wheel reciprocation is adjustable.

The primary objects of the invention are to provide a grinding machine with a mechanism by which the grinding wheel may be moved laterally or axially relative to the work to position it correctly before the feeding and grinding operation starts, and particularly to provide a mechanism of this type which may be so adjusted that the wheel may be repeatedly moved accurately to any predetermined position.

Further objects of the invention are to provide an automatic control for such a wheel positioning mechanism, and particularly to provide a mechanism which is so arranged that the operator may move the wheel manually to a correct and desired position and then feed the wheel into the work to grind the same, and when the grinding operation has been completed, the grinding

wheel will be automatically moved laterally away from the grinding position in a timed relationship with the feeding movement of the wheel.

Other objects are to provide a grinding machine in which the wheel may be reciprocated axially during the grinding operation, and to provide such a construction which may be so adjusted that the wheel may be held stationary or reciprocated during grinding, or the length of the reciprocatory stroke may be adjusted to a desired extent.

It is a further object to combine in a simplified construction a mechanism for repeatedly reciprocating the wheel axially during the grinding operation and means for accurately moving the wheel laterally to adjust it in a correct grinding position, which has such adjustments that the operator may utilize either feature of this construction as desired.

Other objects will be apparent from the following description and the scope of the claims appended hereto.

In accordance with the invention, a grinding machine is provided with mechanism for moving the grinding wheel laterally or axially so that it may be adjusted accurately in a desired grinding position, such as close to a shoulder on the work piece. This may be accomplished by so mounting the wheel spindle that it may slide longitudinally in its bearings. The wheel may be moved manually or automatically, but in the form illustrated the construction is so arranged that the wheel may be moved laterally by a hand lever to its grinding position and it is removed to a second position by automatically operated mechanism. If it is desired to have the machine semi-automatic in operation, the parts may be so constructed that turning the cross feed mechanism to remove the wheel from grinding contact with the work serves to operate a secondary mechanism which moves the wheel axially. This is particularly useful if the work must be ground near a shoulder. To position the wheel accurately relative to such a shoulder, a finely adjustable device is provided to limit the wheel movement and stop it where desired.

In the preferred construction, the automatic withdrawal of the wheel from the grinding position is accomplished by a fluid pressure operated device controlled manually or in 5 timed relation with the wheel feed movement.

A grinding machine of this type is often required to grind a narrow piece of work, and in such a case the wheel may be fed 10 directly into the work. To avoid leaving abrasive grain markings on the finished work surface, it may be desirable to move the wheel axially during the grinding operation. A further feature of this invention involves such a construction which has 15 an adjustable stop so arranged that the length of the axial reciprocating stroke of the wheel may be varied or stopped entirely. This may be accomplished by employing 20 a cam operating member connected to the wheel spindle by means of a follower which may be lifted from the lowest point of the cam to a greater or less extent by a manually adjustable device, such as a screw. 25 A further feature of the invention contemplates combining various features as above outlined so that the grinding wheel may be moved axially continuously during grinding or it may be adjusted into a desired 30 grinding position and left there.

One embodiment of the invention combining all of these features has been illustrated in the drawings, in which like reference numerals indicate like parts; and in 35 which:

Fig. 1 is a cross sectional view illustrating the wheel spindle operating mechanism taken approximately on the line 1—1 of Fig. 2;

Fig. 2 is a cross sectional view of the mechanism taken approximately on the line 2—2 of Fig. 1;

Fig. 3 is a horizontal sectional view taken approximately on the line 3—3 of Fig. 1; 45 and

Fig. 4 is a diagrammatic view showing the operating mechanism for controlling the axial movement of the grinding wheel relative to the wheel feed.

The form illustrated comprises a grinding machine of a suitable construction having a slide 12 mounted on ways on the base of the machine (not shown) arranged to carry the grinding wheel. The wheel spindle 13 is mounted in suitable bearings 14 and 15 on the wheel slide 12 and is driven by a pulley 16 from any suitable source of power. A single grinding wheel may be employed but as illustrated, two grinding wheels 18 and 19 are mounted on the outer end of the spindle 13 and are adapted to grind the different sized portions 20 and 21 respectively of the work piece. The work piece may be mounted in the old and well known form of supports, illustrated dia-

grammatically by a headstock center 22 and a footstock center 23.

As illustrated in the drawings, the mechanism for controlling the axial movement of the grinding wheel spindle is combined with a grinding wheel spindle reciprocating mechanism such as that disclosed in the patent to Belden et al. No. 1,584,717 of May 18, 1926. This mechanism comprises a worm 30 mounted on the outer end of the wheel spindle 13. The worm gear 31 meshing therewith is mounted on a shaft 32 which is rotatably carried in suitable bearings in a housing or casing 33 supported on the end of the wheel slide 12. The shaft 32 is provided with a cam or eccentric 35 which is engaged by a follower 36 mounted on the lower end of an arm 37. The arm 37 is keyed to a sleeve 38 which is rotatably supported in bearings 39 and 40 in the casing 33. A spring 41 is interposed between the casing 33 and the lever 37 to maintain the follower 36 in operative engagement with the face of the cam 35. To transmit the movement of the cam 35 to reciprocate the grinding wheel spindle 13 axially, we provide a yoked lever 45 pivoted on the sleeve 38 which has shoes 46 and 47 pivotally mounted on pins 48 and 49 respectively. The shoes 46 and 47 engage an annular groove 51 on the end of the worm which is threaded on the end of the spindle 13 as shown in Fig. 1. The lever 37 and the yoked lever 45 may be made integral or rigidly connected so that any movement of the follower will be transmitted to reciprocate the grinding wheel spindle axially. In the preferred construction, as illustrated, the lever 37 and the yoked member 45 are separately pivoted so that they may move relative to each other.

A clutch member 55 is provided to operatively connect the lever 37 with the yoked member 45 so that any motion of the lever 37 will be transmitted through the yoked member 45 to move the wheel spindle 13. The clutch member 55 is slidably mounted on the sleeve 38 and has clutch teeth 56 adapted to engage correspondingly shaped openings 57 in the yoked member 45. The clutch member 55 is connected by a pin 58 to the rod 59 which extends from the front of the casing 33. The outer end of the rod 59 is provided with a knob 60 to permit the operator to engage or disengage the clutch. The pin 58 passes through an elongated slot 61 in the sleeve 38 so that any rotary movement of the sleeve 38 is transmitted to the clutch member 55. It will be readily seen from this construction that when the operator pushes the knob 60 inwardly the teeth 56 of the clutch member 55 will engage the yoked member 45 thereby locking the lever 37 and the yoked member 45 so that any movement transmitted by the eccentric

35 to the follower 36 will move the grinding wheel spindle 13 axially.

To attain one of the objects of the invention, a mechanism is provided for moving 5 the wheel spindle axially to bring the grinding wheel 18 into a desired grinding position, such as into contact with the shoulder 65 on the work piece 20. As illustrated in Fig. 4 of the drawings, a lever 70 is pivotally mounted on a stud 71 on the wheel slide 12. The outer end of the lever 70 is pivoted by a pin 72 to a connecting link 73, which is in turn pivotally connected by a pin 74 to a short lever 75. The lever 75 is 10 rigidly mounted on the shaft 76 which is mounted in a suitable bearing in the casing 33. The lower end of the shaft 76 is provided with a gear segment 77 which meshes with a pinion 78 mounted on the upper end 15 of a shaft 79. A cam 80 is mounted on the lower end of the shaft 79 and is rigidly secured thereon by a nut 81. The upper end of the yoked member 45 is provided with a follower roller 90 which is adapted to contact 20 with the surface of the cam 80. A spring pressed plunger 91 is interposed between a projection of the casing 33 and the upper end of the yoked member 45 to hold the follower 90 in operative contact with the 25 cam 80. It will thus be readily seen that movement of the lever 70 in the direction of the arrow (Fig. 4) will move the gear segment and pinion 78 to turn the cam 80 in the direction of the arrow, as shown in 30 Fig. 3. Rotation of the cam 80 will move the roller 90 and consequently the upper end of the yoked member toward the left as viewed in Figs. 1 and 3 and thereby move the grinding wheel into engagement with 35 the shoulder 65.

To automatically withdraw the grinding wheel from engagement with the shoulder at the completion of the grinding operation, mechanism is provided to operate in timed 45 relation with the wheel feeding mechanism. In the preferred construction, an air operated mechanism comprising a cylinder 95 pivoted on a stud 96 within the casing 33 is utilized. The cylinder 95 is provided with 50 a piston 97 operatively connected with the gear segment 77 by a connecting rod 98. The rod 98 is connected to the segment by a stud 99 so that any movement of the piston 97 will be transmitted to move the gear segment. To operate this mechanism in timed 55 relation with the wheel feeding mechanism, a cam 105 (Fig. 4) is mounted on the shaft 106 which is rotated in timed relation with the cross feed screw (not shown). A follower 107 is mounted on the end of a rod 108, which is formed as an integral part of the valve plunger 109 adapted to slide within the valve casing 110. The follower 107 is maintained in operative contact with the 60 surface of the cam 105 by a spring 112 in-

terposed between the end of the valve casing 110 and a collar 113 fixed on the rod 108. The pipe 115 is connected with any suitable supply of compressed air so that as the cam 105 rotates in the direction of the arrow, as 70 shown in Fig. 4, the valve 109 will be moved toward the right closing exhaust port 111 and thereby serve to open the port 116 to admit air into the valve chamber. The air passes through the port 117 and pipe 118 75 and through the port 119 into the cylinder chamber 120. This pressure will move the piston 97 toward the right, as viewed in Figs. 1 and 3, to automatically move the gear segment in a direction opposite to the arrow shown in Fig. 3. The tension of the spring pressed plunger 91 will maintain the follower 90 in contact with the surface of the cam 80 and thereby move the wheel spindle toward the right, as viewed in Fig. 1, and 80 withdraw the grinding wheel 18 from contact with the shoulder 65 of the work. It will be seen that by movement of the lever 70 toward the left at the starting of the grinding operation, the wheel spindle 13 85 will be moved axially to bring the grinding wheel 18 into operative engagement with the shoulder 65. The cam 80 is so shaped that as the cam is rotated due to movement of the lever 70, the thrust of the wheel spindle against the surface of the cam is sufficient to prevent displacement of the grinding wheel during the grinding operation. On completion of the grinding operation the feed mechanism is operated to remove the 90 wheel from the work and the cam 105 will be thereby turned in the direction of the arrow as shown in Fig. 4 to open the valve 109 and admit air into the cylinder chamber 120. This air pressure will automatically rotate 95 the cam 80 in the opposite direction, and due to the tension of the spring pressed plunger 91, turn the wheel spindle 13 to an inoperative position with the grinding wheel 18 out of engagement with the shoulder 65. 100

The grinding wheel may be moved accurately to any desired position relative to the work by limiting the movement of the gear segment 77. This may be simply accomplished by means of a set screw 130 (Fig. 3) 105 suitably threaded through a part of the casing wall 33 and adapted to project into the path of the segment 77. By adjusting this screw to given positions, the movement of the grinding wheel toward the left is limited as desired, and the operator has thereby a very simple means by which he may position the wheel always in the same position for successive movements thereof. An adjustable screw 131 projecting likewise 115 through the casing limits the movement of the gear segment 77 in the opposite direction. 120

If it is desired to utilize the automatic reciprocating feature of the invention for 130

moving the wheel back and forth axially during the grinding operation, the clutch member 55 is engaged with the corresponding clutch teeth 57, thus connecting the rocking lever 37 with the yoke 45 so that rotation of the cam 35 tends to swing the lever 37 and the yoke 45 back and forth and move the wheel spindle correspondingly. The other portions of the mechanism which serve 10 to position the wheel relative to the shoulder 65 are disconnected during this reciprocatory movement of the wheel. It is possible to limit the extent of axial reciprocating movement of the wheel in one direction accurately by means of a set screw 135 which is threaded through a portion of the housing 33 and projects into the path of one of the arms of the yoke lever 45. The set screw 135 may be removed from contact with the 20 yoke 45 permitting the latter to rock freely but if moved into engagement therewith it tends either to hold the cam follower 36 away from the cam 35 entirely and thus prevent reciprocation of the grinding wheel or 25 it may be adjusted to an intermediate position and hold the follower 36 out of contact with the low part of the cam 35 but permit the higher portion of the cam to strike it and so reciprocate the wheel spindle through 30 a limited distance. In this way one may adjust the throw of the wheel and cause it to reciprocate either a short distance or a greater distance or not at all. In order to stop the reciprocation of the wheel spindle 35 quickly and easily without reference to the screw 135, a stop 137 having a cam face 138 on its inner end is arranged to engage the end 139 of the spindle. This stop 137 is in the form of a rocking lever mounted on a 40 pin 140 passing through the casing 33 and having a handle 141 projecting therefrom so that the operator may reach and move it readily. These various mechanisms as described make it possible to move the wheel 45 laterally either continuously through a variable stroke or when desired by the operator to position the wheel accurately in a given grinding position.

Having thus described our invention, 50 what we claim as new and useful is:—

1. A grinding machine comprising a work support, a wheel slide mounted for feeding movement towards the work, a grinding wheel thereon, a rotatable, axially movable spindle to support said grinding wheel, manually operable means to move said spindle axially to locate the grinding wheel in a predetermined grinding position, and automatically operated mechanism to move said 55 spindle axially in the opposite direction to remove the grinding wheel from said grinding position.

2. A grinding machine comprising a work support, a grinding wheel, a rotatable spindle for said wheel, a wheel slide support-

ing the spindle and wheel which is movable to feed the wheel into the work, means to move said spindle axially relative to said slide to locate the grinding wheel in a predetermined grinding position, and fluid pressure operated mechanism to move said spindle in the opposite direction. 70

3. A grinding machine comprising a work support, a grinding wheel mounted for movement towards and from the work, a rotatable axially movable spindle to support said wheel, manually operable means to move said spindle axially to locate the grinding wheel in a predetermined grinding position, and a cam controlled mechanism operating to automatically move said spindle axially in the opposite direction. 75

4. A grinding machine comprising a work support, a grinding wheel, a rotatable spindle to support said wheel, a cam mechanism to move said spindle axially to locate the grinding wheel in a desired grinding position, and a cam controlled pneumatic mechanism to automatically move said spindle in the opposite direction. 80

5. A grinding machine comprising a work support, a grinding wheel, an axially movable, rotatable spindle to support said wheel, manually operable means to move said spindle axially and position the grinding wheel in a desired position relative to a shoulder on the work and automatic mechanism operating in timed relation with a moving part of the machine to move said spindle in the opposite direction to remove the grinding wheel from said shoulder on completion of the grinding operation. 90

6. A grinding machine comprising a work support, a grinding wheel, a slide therefor movable to feed the wheel into the work, an axially movable, rotatable spindle arranged to move the wheel laterally, means for moving the spindle axially to locate the wheel in a given grinding position, and means operable in timed relation with the grinding wheel feeding movement when the wheel is removed from the work to move the spindle axially and move the wheel laterally from said grinding position. 105

7. A spindle reciprocating mechanism for a grinding machine comprising a grinding wheel spindle, means to utilize the rotary movement of said spindle to reciprocate the same axially, means to prevent reciprocation of the wheel spindle, manually operable mechanism to move the grinding wheel spindle axially to locate and hold the grinding wheel in a definite grinding position and automatically operated mechanism to move the grinding wheel spindle in the opposite direction. 120

8. A grinding machine comprising a work support, a grinding wheel positioned for grinding the same, an axially movable, rotatable spindle for the wheel, mechanism 130

- for reciprocating the spindle axially including a rotatable cam, a rocking lever operatively connected to the spindle and moved by said cam, and an adjustable device which 5 may be brought into engagement with one of said movable parts to limit the length of stroke of the spindle.
9. A grinding machine comprising a grinding wheel, a rotatable spindle to support said wheel, means to move said spindle axially to a definite position including a yoked member engaging a groove in the end of the wheel spindle, a cam contacting with a portion of said yoke and adapted to move 10 said yoke to transmit an axial movement to the grinding wheel spindle and a lever mechanism operating through a gear segment and pinion to rotate said cam through the required amount.
10. A grinding machine comprising a wheel spindle, a pivotally mounted yoked member engaging an annular groove in said spindle, a cam contacting with said yoked member to move the grinding wheel spindle 15 axially, a spring pressed plunger engaging said yoked member to maintain the same in contact with the surface of the cam, a gear segment and pinion to rotate said cam, a lever to manually move said segment to rotate said cam and thereby move the grinding wheel axially to a desired position relative to the work, and a pneumatic cylinder mechanism controlled by a cam operated valve to automatically move said gear segment 20 in the opposite direction and thereby remove the grinding wheel from said position when the grinding operation has been completed.
11. A grinding machine comprising a support for rotatable work, a grinding wheel slide arranged for feeding the wheel towards and from the work, a spindle mounted on said slide and arranged for axial movement at right angles to the feeding 25 movement, a grinding wheel thereon and means to move the spindle rapidly along its axis and adjustably position the wheel relative to the work which includes a member serving to hold the wheel axially immovable 30 during the grinding operation and an adjustable stop for limiting the axial movement of the wheel spindle in one direction whereby the wheel may be accurately and repeatedly moved along the work to and from a predetermined grinding position.
12. A grinding machine comprising a work support, a wheel slide arranged for feeding movement towards and from the work support, bearings on said slide, a rotatable grinding wheel spindle mounted for 35 axial movement within said bearings, a grinding wheel thereon, means to move the spindle axially within the bearings and to hold the same immovable during the grinding operation, and an adjustable stop de-
- vice for limiting the axial movement of the spindle and locating the wheel accurately in any predetermined grinding position relative to the work.
13. A grinding machine comprising a work support, a wheel slide arranged for feeding movement towards and from the work support, bearings on said slide, a rotatable grinding wheel spindle mounted for 40 axial movement within said bearings, a grinding wheel thereon, means to move the spindle axially within said bearings including a cam which is so shaped as to resist movement of the spindle in the opposite direction and hold the same during the grinding operation, and an adjustable stop device for limiting the axial movement of the spindle and locating the wheel accurately in any predetermined grinding position relative to the work.
14. A grinding machine comprising a work support, a wheel slide arranged for feeding movement towards and from the work support, bearings on said slide, a rotatable grinding wheel spindle mounted 45 for axial movement within said bearings, a grinding wheel thereon, means to move the spindle axially within the bearings and to hold the same immovable during the grinding operation, an adjustable stop device for limiting the axial movement of the spindle and locating the wheel accurately in any predetermined grinding position relative to the work, and automatically actuated means to move the wheel axially from said adjusted position after the grinding operation.
15. A grinding machine comprising a work support, a wheel slide arranged for feeding movement toward and from the work, bearings on said slide, a rotatable 50 axially movable spindle in said bearings, a grinding wheel mounted thereon, means for moving said spindle and wheel axially within the bearings to position it accurately relative to the work for a grinding operation and means operated in timed relation with the wheel feeding movement to move the wheel axially within its bearings away from the grinding position when the grinding operation has been completed.
16. A spindle operating mechanism for a grinding machine comprising a wheel slide, spindle bearings thereon, an axially movable, rotatable spindle supported in said bearings, a grinding wheel thereon, means including a yoked member connected to move the spindle in an axial direction, means including a rotatable cam to oscillate 55 said yoked member and reciprocate the wheel spindle, and manually operable means to rock said yoked member to locate and hold the grinding wheel in a definite predetermined grinding position.
17. A spindle operating mechanism for a 60

- grinding machine comprising a wheel slide, spindle bearings thereon, an axially movable, rotatable spindle supported in said bearings, a grinding wheel thereon, means including a pivotally mounted yoked member which is connected to move the spindle in an axial direction, means including a rotatable cam to oscillate said yoked member and reciprocate the wheel, manually operable means to rock said yoked member and to hold the wheel in a predetermined position for grinding and automatically operated mechanism to move the grinding wheel axially in the opposite direction after the grinding operation has been completed.

18. A grinding machine comprising a work support, a wheel slide arranged for feeding movement towards and from the work support, a rotatable grinding wheel spindle mounted for axial movement on said slide, automatic mechanism to reciprocate the wheel spindle axially during the grinding operation, means for rendering said mechanism inoperative, means for adjusting the grinding wheel along its axial line to position and hold it for a grinding operation, and an adjustable stop cooperating therewith for limiting said wheel adjustment so that the wheel may be repeatedly and accurately moved to and from a predetermined grinding position.
